UNITED STATES PATENT OFFICE.

PHILIP A. MYERS, OF ASHLAND, OHIO, ASSIGNEE TO F. E. MYERS & BROTHER, OF SAME PLACE.

DESIGN FOR A DOOR-HANGER PULLEY-FRAME.

SPECIFICATION forming part of Design No. 33,590, dated November 20, 1900.

Application filed June 20, 1900. Serial No. 21,021. Term of patent 14 years.

To all whom it may concern:

Be it known that I, PHILIP A. MYERS, a citizen of the United States, residing at Ashland, in the county of Ashland and State of Ohio, have invented and produced a new and original Design for Door-Hanger Pulley-Frames, of which the following is a specification, reference being had to the accompanying drawings, forming a part thereof.

Figure 1 is a side elevation of a pulley-frame, showing my new design; Fig. 2, an end elevation showing that aspect thereof; Fig. 3, a perspective view of my new design, and Fig. 4 a side elevation showing the reverse side to that illustrated in Fig. 1.

As shown in the drawings, the leading and material feature of my design consists of an upper outline with a central raised portion *a* and lateral lower portions *b*, with curved sides *c* and a straight cross or base line *d* disposed or arranged as shown in Fig. 1. The outline *a* is a part of a circle, while the lines *b* are also curves, but are more gradual. The line *a* continues round, as shown at *a'*, and borders a raised surface *a''*. (Shown more clearly in Fig. 2.) The curved or semicircular line *a'''*, outside or below the line *a'*, meets the line *b* and leaves another raised surface *a''''*. The general surface *e* of the frame on the side shown in Fig. 1 and at the right-hand side in Fig. 2 occupies a plane to one side or back of the raised surfaces described, but recedes to form a depressed surface *f*, as indicated by dotted lines in Fig. 2. Within the

lines *c* are raised surfaces *f'*, which border 35 the depressed surface *f*. Lines *d'* and *d''*, joined by short end lines, form a substantially parallel-sided opening. The surface *d'''* between the line *d'* and line *d* is rotund, as more clearly indicated in Fig. 2.

Viewing the design of my frame as shown in Fig. 2 particularly, it will be seen that besides the lines and surfaces above described it also presents substantially parallel lines *g*, joined by the cross-line *g'*, just below which 45 is another cross-line *g''*, which latter joins on the right side with the surface *e* and on the left side with the corresponding surface *e'*. The outline of said frame is completed by the upright line *h* forming a surface opposite to 50 the surfaces *e* and *f* and joining a curved line *h'* and another straight line *h''* to complete the upper part of this portion of the frame, while the curved line *i* joins a practically straight line *i'*, which, with the line *i''*, produces a horn-like projection.

Having thus fully described my invention, what I claim as new, and desire to secure by Letters Patent, is—

The design for a door-hanger pulley-frame, 60 as herein shown and described.

In testimony whereof I have signed my name to this specification in the presence of two subscribing witnesses.

PHILIP A. MYERS.
